PULL-SWITCH.

1,401,276.

Specification of Letters Patent. Patented Dec. 27, 1921.

Application filed February 12, 1919. Serial No. 276,467.

To all whom it may concern:

Be it known that I, ARVID H. NERO, a citizen of the United States, and a resident of the city of New Britain, county of Hartford, and State of Connecticut, have invented certain new and useful Improvements in Pull-Switches, of which the following is a specification.

My invention relates to pull switches, and particularly to a switch operating mechanism, the object of my invention being to provide a switch of the general hill and valley type, in which a quicker and wider break between the switch bar and the switch terminals is attained than has hitherto been secured in switches of this type. The invention involves certain other features of improvement shown in the accompanying drawings, in which,

Figure 1 is a dropped perspective of a pull socket interior in which the switch forming the subject matter of my invention is illustrated;

Fig. 2 is a broken vertical section through the socket;

Fig. 3 is an inverted plan of the upper insulating button of the socket body; and

Fig. 4 is a plan of the lower button showing the switch terminals in place and certain metal parts in section.

While the present invention is applicable to pull switches of various types I have illustrated it in the accompanying drawing embodied in a lamp socket. The usual metallic casing is shown in Fig. 2, and comprises a cap 10 and shell 11, which house the insulating body of the socket carrying screw shell contact 12 and center contact 13. The socket body comprises a pair of insulating buttons 14 and 15 spaced apart by standards 16, 17 and 18, to afford a chamber for the reception of the switch mechanism. The standards 16 and 17 are adapted to receive binding screws 19 for the respective lead wires which pass thereto through marginal channels 20 in the upper button 14. The standard 17 is provided with a foot piece 21, which overlies the base flange of the screw shell 11 and makes direct electrical connection therewith. The standard 16 is offset at one end to form a switch terminal 22, provided with a lug 23 engaged by a screw bolt 24 passing through the button 15. The cooperating switch terminal 25 lies diametrically opposite the terminal 22 and is provided with a lug 26 pierced by the screw bolt 27, the head of which overlies the base of the center contact 13. Within the switch chamber inclosed between the buttons 14 and 15 and the insulating lining 28 of the socket, is arranged the switch mechanism. It is mounted upon a spindle 29 freely journaled in bearing sockets 30 and 31, formed in the upper and lower buttons, respectively. A well 32 eccentric with and opening to the spindle bearing 30 in the button 14, receives the upper end of the ratchet return spring 33, the offset terminus 34 of which is engaged in a slot 35 opening to the well 32 and serving to hold this end of the spring against rotation. The offset terminus 36 at the opposite end of the spring engages a tongue 37 struck up from the tension adjustment disk 38, which has a bearing hub 39 free on spindle 29. Arcuate teeth 40 struck downward from disk 38 engage arms 41 of the star plate 42 in a direction to insure the rotation of said disk and star plate together in both directions, *i.e.*, either clockwise under the torsion of the spring 33, or counter-clockwise under the pull of the chain C engaging the chain rail 43, which is insulated from the star plate 42 by the usual fiber carrier sheet. It is obvious that by rotating the adjusting disk 38 quarter turns contra-clockwise with relation to the star plate 42, the tension of the spring 33 may be increased as far as desirable to insure a prompt return of the chain rail after actuation of the switch. This construction of the adjusting mechanism for the return spring is not only cheaper than the usual displaceable abutment engaging the button 14 but has the advantage of enabling the manufacturer to permanently adjust the return spring to proper tension before the switch leaves the factory. Where the adjusting abutment is readily accessible to the wireman it frequently happens that excessive tension is placed on the spring 33, with resultant strain on the parts which injuriously affects the switch mechanism if it does not actually cause rupture of the spring 33. By rendering the adjuster inaccessible to the wireman, the correct tension imparted to the spring at the factory is practically assured of permanency.

Below the star plate 42 is a ratchet disk 44, having tongues 45 up-turned into an

gagement with the arms 41 of the star plate 42. This ratchet disk 44 is rigid with the spindle, the lower portion of which is enlarged to form an abutting shoulder to which the disk is soldered. Extending downwardly from the opposite margins of the disk 44 are arcuate tongues 46 inclined at an angle of about 45° to the plane of the disk 44, and engaging marginal notches 47 in the body 48 of the switch bar which carries at its opposite ends the contact brushes 49 and 50. Between the ratchet disk 44 and the switch bar 48 is freely interposed a coil spring 51, the function of which is to force the switch bar down upon its hill and valley course.

The switch terminals 22 and 25 upon which the brushes 49 and 50 of the switch bar bear in the "on" position of the switch 20 alternate with arcuate ratchet bosses 52 and 53 formed in the button 15 surrounding the bearing recess 31 for the spindle 29 and the concentric circular recess 54, which affords a clearance for the arcuate tongues 46 of the 25 ratchet plate as they rotate during the actuation of the switch. The crests of the bosses 52 and 53 terminate sharply at points well above adjacent portions of the terminal strips 22 and 25, which at these ends are 30 substantially flat, but at their other ends 55 and 56 are inclined upwardly. These ends 55 and 56 and the inclines of the ratchet bosses 52, 53 serve as detents which delay the throw of the switch bar and insure a 35 quick make-and-break between the contacts when the switch is actuated.

The operation of the mechanism is readily understood;—Assuming the spring 33 to have been placed under proper tension by 40 the rotary adjustment of the disk 38 with relation to the star plate 42, the chain rail is halted in normal stop position by the impingement of its fiber carrier plate against the standard 17. If the chain C is now 45 pulled out through the chain bell 57 in standard 18, the star plate is rotated against the action of its return spring 33 in a direction to carry with it the ratchet disk 44 by reason of the engagement of its tongues 45 50 with the arms 41 of the star plate. During this rotation the arcuate tongues 46 of the ratchet disk 44 which are in engagement with the notches 47 in the switch bar 48, cause the brushes 49 and 50 of the latter to 55 travel up the inclines of the ratchet bosses 52, 53, or the upwardly inclined ends 55, 56 of the switch terminals. As the switch bar advances its rotation is increasingly opposed by the inclines of its course by reason of the pressure of the spring 51, which is gradually compressed against the ratchet disk fast on the spindle 29. The opposition to its rotation causes the switch bar to 60 lag behind the ratchet disk 44, and to ride up the inclined sides of its arcuate tongues

46. Upon reaching the crest of the inclines and passing thereover, the switch bar 48 is forcibly depressed by the spring 51, and is thrown rapidly forward in the direction of its rotation as it rides down the inclines of the tongues 46. The latter, thus impart a positive forward throw to the switch bar, and materially increase the distance of the break between the terminals 22, 25, and the switch bar brushes 49 and 50. A much heavier current may be safely broken in a switch of this construction than is now possible in switches of this general type.

Obviously upon release of the chain the return spring 33 rotates the carrier 43 back 80 to stop position, riding the star plate 42 over the ratchet disk 44 and placing the arms 41 in position to engage the ratchet teeth 45 and move the switch bar to its next position on the succeeding pull of the chain C.

I do not limit my invention to the precise form shown for the arcuate tongues 46, or to other details of construction shown and described, which may be variously modified without departing from what I claim as my 90 invention.

I claim:

1. An electric switch of the hill and valley type, comprising a rotary switch bar following the hill and valley course, a switch 95 spindle on which said bar freely rotates, an actuating rotor on the spindle, said rotor having inclined arms spaced from the spindle and engaging said switch bar and up which the latter rides during the rise of 100 said bar over the hills of its course, and spring means interposed between said rotor and switch bar to force the bar down said inclines with a positive forward throw in the direction of its rotation after passing 105 the crest of a hill in its course.

2. In an electric switch of the construction specified in claim 1, ratchet means for operating the rotor.

3. In an electric switch of the construction specified in claim 1, the switch bar being recessed to receive the inclined arms of the rotor.

4. In an electric switch of the construction specified in claim 1, the switch bar 115 being marginally notched to receive the inclined arms of the rotor.

5. In an electric switch an actuating rotor comprising a plate having offset arms provided with cam inclines in combination with 120 a switch bar having guide ways through which said arms pass as the switch bar rides up the inclines thereof on the actuation of the switch.

6. In an electric switch, an actuating 125 ratchet, a return spring for rotating the same in one direction and an adjusting disk engaging one end of the spring and rotatable with relation to the ratchet to regulate the spring tension, and means for detachably 130

engaging said disk and ratchet to insure their synchronous rotation during the operation of the switch.

7. The combination with a construction such as specified in claim 6, of a fixed abutment for the opposite end of return spring.

8. The combination with a construction such as specified in claim 7, of a switch body and a fixed engagement between said body and the opposite end of the return spring.

In testimony whereof I have signed my name to this specification.

ARVID H. NERO.
